Primary Examiner — Khawaja Anwar(74) *Attorney, Agent, or Firm — Greenberg Traurig, LLP*(57) **CLAIM**

The ornamental design for an ice pack, as shown and described.

DESCRIPTION

FIG. 1 is a perspective view of an ice pack showing the new design;

FIG. 2 is a front view thereof;

FIG. 3 is a rear view thereof;

FIG. 4 is a left side view thereof;

FIG. 5 is a right side view thereof; and,

FIG. 6 is a top side view thereof, a bottom side view being identical to the top side view.

Broken lines are for illustrative purposes only and form no part of the claimed design.
